UNITED STATES PATENT OFFICE.

GEORGE AUGUSTUS HERRON, OF PEMBROKE, ONTARIO, CANADA.

CAR-STAKE.

1,250,314.

Specification of Letters Patent. Patented Dec. 18, 1917.

Application filed April 17, 1917. Serial No. 162,688.

To all whom it may concern:

Be it known that I, GEORGE AUGUSTUS HERRON, a subject of the King of Great Britain, and a resident of the town of Pembroke, in the Province of Ontario and the Dominion of Canada, have invented certain new and useful Improvements in Car-Stakes, of which the following is a full description.

10 This invention relates to improvements in car stakes and the objects of the invention are to permit of the stakes along one side of a railway lumber car being simultaneously released and so facilitate unloading the car, to readily adjust the chain or other flexible member which connects opposite stakes and engages with the top of the logs thereby holding the logs compactly together and preventing their rolling over 15 each other due to vibration when the car is running, to prevent the stake locking means from inadvertently loosening and generally to simplify the several parts and adapt the same to better perform the functions required of them.

For a complete understanding of my invention reference is made to the following specification and accompanying drawings in which,

20 Figure 1 is a side elevation of a car embodying the present invention.

Fig. 2 is a fragmentary plan view of the same.

Fig. 3 is an end view of the car illustrated in Fig. 1.

Fig. 4 is a fragmentary perspective view of the tubular rod carrying the stake locking means.

Fig. 5 is a perspective view of an alternative form of stake.

Fig. 6 is a fragmentary side elevation, partly sectional, of the tubular member carrying the stake locking means and showing an alternative method of actuating the same.

25 Like characters of reference refer to like parts in the several figures.

Referring to the drawings, A represents a railway lumber car of the usual type equipped with the usual stakes B. The sides 30 of the car A are provided with a plurality of equidistantly spaced brackets 10 which consists of a back wall 11 having a plurality of orifices therethrough whereby the brackets may be secured in position by bolts 35 12 or the like.

The side walls 13 of the brackets are

formed integral with the back walls 11 and the inner face of the said side walls taper toward the bottom, the front of the brackets being opened and designed to be closed by 60 a tapered locking member 14 provided with an offset end 15 which is rigidly secured to the tubular spindle 16.

This tubular spindle is slidably mounted in the brackets 17 located intermediate of the brackets 10 and the end of the spindle is formed with a threaded portion with which the screw 18 makes threaded engagement.

This screw is rotatably mounted in the bracket 19 and to prevent longitudinal 70 movement of the screw a pair of collars 20 are mounted thereon and designed to engage with the opposite faces of the said bracket.

Rotary motion is transmitted to the screw 18 by the hand lever 21 and when the spindle 16 has been moved to the desired position in which the locking members 14 engage with the brackets 10, the hand lever 21 is engaged by a locking member 22, so that although the car may be subjected to 80 undue vibration, there is no liability of the screw 18 working loose.

The car stakes B consist of a plurality of tubular members 23 having their outer wall corrugated or serrated as shown at 85 24, the lower ends of the tubular members being provided with a tapered portion 25 designed to engage with the brackets 10.

The upper end of the stakes are provided with enlarged heads 26 which may consist 90 of flanges threaded or otherwise fastened thereon or may be formed integral with the said stake.

These car stakes are located along both lateral faces of the car A, being arranged in 95 pairs directly opposite each other and when the car is loaded with logs in the manner shown in Fig. 3, the chain 27 or other flexible member extends across the top of the load to prevent displacement and rolling of 100 the logs.

This chain is formed of two portions with the outer ends of each provided with elliptical links 28 adapted to engage with the stakes B and when the chain is being tightened 105 these links will engage with the corrugations 24.

In tightening the chain it is only necessary to adjust the length of the same on the lever downwardly, and the chain will be 110 tightened.

Referring now to Fig. 5, an alternative

form of stake B' is shown which is substantially T-shaped in cross section with the transverse member of the T designed to engage with the logs, the web of the T being 5 serrated as shown at 31 to engage with the links 28 of the chain 27.

In other respects these stakes are similar to those already described being provided with tapered ends 25 to engage with the 10 brackets 10.

In Fig. 6 an alternative means for actuating the locking members is illustrated in which the spindle 17^a is provided with annular flanges 32 adapted to embrace the enlarged end 33 of the screw 34 making threaded engagement with the brackets 35 mounted on the car, which screw is provided with a hand lever 36 whereby it is manually actuated.

20 When a car equipped in this nature is in use, the stakes B are positioned and the car loaded with logs or lumber whereupon the chain 27 is positioned with the links 28 engaging the corrugations or serrations 24 of 25 the stakes and the lever 29 is then adjusted and on depression of the lever the chain 27 is tightened on the load.

When unloading this car the operator rotates the hand lever 21 so moving the tubular spindle 16 in a longitudinal direction thereby withdrawing the locking members 14 from engagement with the brackets 10 and permitting the stakes under the pressure of the load to be moved laterally and thus 35 simultaneously released.

When the stakes are released, the chains 27 prevent the stakes from fouling with the logs and it will be readily seen that by providing the serrations or corrugations, the 40 chain cannot slip.

It will be understood that the tubular spindle 16 does not rotate, but only moves in a longitudinal direction and it will also be seen by reference to Fig. 1, that the 45 screw 18 is only capable of rotation and does not move in a longitudinal direction, the necessary force to actuate the spindle 16 being derived from the rotation of the screw.

When the locking members 14 are actuated by that type of the invention illustrated in Fig. 6, the lever 36 is manually rotated and the screw 34 moves in a longitudinal direction drawing the spindle 17^a with it to disconnect the members 14 from the brackets 55 10.

One of the chief differences between this type of mechanism and that illustrated in Figs. 1 and 2, is that the screws 34 in moving longitudinally restricts the passage be-

tween adjacent cars, so that the operator has 60 to stand well between the cars when actuating the lever 36, whereas in that form illustrated in Figs. 1 and 2, the screw 18 does not move longitudinally and there is always sufficient clearance between the cars to permit 65 of the operator of the lever 21 standing without discomfort.

From this description it will be seen that I have invented a car stake which can be advantageously employed on lumber cars 70 and wherein the several stakes on one side of the car can be simultaneously released to liberate the lumber, the several parts being of an extremely simple nature and not liable to get out of repair.

As many changes could be made in the above description and many apparently widely different embodiments of my invention within the scope of the claims constructed without departing from the spirit 80 or scope thereof, it is intended that all matter contained in the accompanying specification and drawings shall be interpreted as illustrative and not in a limited sense.

What I claim as my invention is:

1. The combination with a car of a plurality of stakes operatively mounted thereon and means for simultaneously releasing said stakes consisting of locking members, a non-rotatable and longitudinal movable 90 spindle carrying said members, and a screw coacting with the said spindle.

2. In combination with a car of a plurality of car stakes operatively mounted thereon having corrugations or serrations 95 in the outer wall, a chain extending between the said stakes having links engaging with the corrugations, a tubular non-rotatable spindle mounted on the car, locking members carried by the spindle designed to lock the stakes in position, and a screw designed to move the spindle in a longitudinal direction.

3. In combination with a car of a plurality of stakes operatively mounted thereon and arranged in pairs having their outer wall corrugated or serrated, means for locking the stakes in position, chains engaging with the stakes, lever means for tightening the chains, a longitudinal extending non-rotatable spindle slidably mounted on the car, locking means coacting with the stakes carried by the spindle, and screw means for actuating the spindle.

In witness whereof I have hereunto set 115 my hand.

GEORGE AUGUSTUS HERRON.
